UNITED STATES PATENT OFFICE.

CHARLES SEBASTIAN, OF ST. LOUIS, MISSOURI, ASSIGNOR TO THE UNION STAPLE SEAM RE-ENFORCING COMPANY, OF MISSOURI.

STAPLE-SETTING MACHINE.

SPECIFICATION forming part of Letters Patent No. 634,859, dated October 10, 1899.

Application filed March 14, 1898. Serial No. 673,792. (No model.)

To all whom it may concern:

Be it known that I, CHARLES SEBASTIAN, a citizen of the United States, residing at St. Louis, in the State of Missouri, have invented 5 certain new and useful Improvements in Staple-Setting Machines, of which the following is a full, clear, and exact description, reference being had to the accompanying drawings, forming a part hereof.

10 My invention relates to improvements in staple-setting machines; and it consists in the novel combination and arrangement of parts, as will be hereinafter more particularly described, and pointed out in the claims.

15 In the drawings, Figure 1 is a side elevation of my complete invention. Fig. 2 is a front view of the stationary jaw or head of the machine. Fig. 3 is a vertical section taken on the line *a a* of Fig. 2. Fig. 4 is a plan view 20 of the spring and lug which is secured to the head. Fig. 5 is a front view of the head of the machine with parts removed therefrom.

25 Fig. 6 is a rear view of my complete invention. Fig. 7 is a vertical transverse section taken on the line *b b* of Fig. 8. Fig. 8 is a similar section taken on the line *c c* of Fig. 7. Fig. 9 is a section taken on the line *d d* of Fig. 1. Fig. 10 is a detail plan view of the cam which 30 operates the lever forming the lower jaw.

35 Fig. 11 is a plan view of the receptacle for containing the staples. Fig. 12 is a section taken on the line *e e* of Fig. 1, and Fig. 13 is a plan view of the cam and rear end of the lever for operating the reciprocating plunger.

40 The object of my invention is to construct a machine to be employed for automatically feeding and setting staples for securing leather or other material together, thereby dispensing with hand or machine stitching usually employed, and is especially adapted for uniting the various leather parts comprising the upper portion of shoes; but the machine is equally applicable for other purposes where like results are desired to be obtained 45 without departing from the nature of my invention.

Briefly stated, the invention consists of a main drive-shaft operated continuously or intermittently by a belt-pulley and means co-50 operating with the latter and under the control of the operator; a cam secured to said

shaft and engaging with one end of a pivoted lever the opposite end of which forms the lower movable jaw of the machine, said cam elevating the jaw to its highest position, and 55 a spring for causing the same to assume its normal position; a second cam secured to said shaft and co-operating with the inner forked end of a second pivoted lever, the outer end of which vertically reciprocates a plunger 60 which is brought in contact with the staple under the same, whereby the staple is forced down and through a guideway in the head of the machine and its legs brought in contact with the die carried by the longer jaw and 65 turned after they have been passed through the material to be united; an inclined track leading directly from the head to and passing into a rotating feed cylinder or receptacle 70 upon which the staples slide from the receptacle to the head of the machine and under the plunger; a spring-plate secured to the head of the machine the free end of which is provided with an inclined lug which is normally located in a correspondingly-shaped 75 groove formed in the end of the track; a bracket secured to the rear of the machine; a spindle secured and supported by the same; a tubular projection forming a part of the rotating receptacle and adapted to turn upon 80 said spindle and in consequence turn said receptacle; a large grooved belt-pulley secured to said tubular extension; a small grooved belt-pulley secured to the projecting end of the power-shaft; an idle grooved pulley mov- 85 ably supported on a spindle secured to the machine; a suitable belt passed over said pulleys, whereby when the power-shaft is rotated the receptacle containing the staples to be fed to the track is also turned or rotated; 90 a sliding cover for said receptacle; a circular opening in one end of said receptacle through which the upper end of the track passes; a hopper secured to the inner projecting end of the spindle located within the receptacle, the 95 open end of which is in a line with the upper end of the track; plates secured to the inner curved surface of the receptacle for elevating the staples contained therein and permitting them to drop into the hopper; a ring secured 100 within the receptacle and located at one end thereof, said ring forming a brush encircling

the track, whereby only those staples that are properly placed upon the track are permitted to pass from the receptacle, and other details in the construction, as will be herein-
5 after more fully described.

Referring to the drawings, 1 represents the body of the machine, which is preferably cast in one piece, and having a forward head 2, forming one jaw, and an extension 3, terminating in bearings 4, which operate as a guide for the vertical reciprocating rod 5. To this rod is adjustably secured a collar 6, and loosely secured to the opposite sides of the same and depending therefrom are two links 7, to the lower ends of which are loosely secured the forked ends 8 of a pivoted lever 9, a shaft 10 passing through the opposite sides of the body of the machine and lever. The rear end of the lever 9 also terminates in a fork 11, which embraces a cam 12, fixed to the rotating power-shaft 13, whereby a reciprocating motion is given to the forward end of the said lever, and consequently the rod 5, when motion is imparted to the said shaft by the belt-wheel 14. Located adjacent to the cam 12 is a second cam 15, which coöperates with the rear end of a second pivoted lever 16, also movably secured to the body of the machine by a shaft 17, the forward end of which is adapted to move to and from the stationary jaw or head 2 and forms the lower jaw of the machine. Thus it will be seen that when motion is imparted to the shaft 13 the forward end of the lever 16 will be elevated toward the fixed head 2 by the cam 15, the spring 18 forcing the said lever in the opposite or normal position after the cam has been sufficiently turned to cause the flat surface of the same to come opposite the rear end of the lever—or, in other words, the cam operates the lever in one direction and the spring operates in the opposite direction. Any well-known clutch mechanism is employed in connection with the drive belt-wheel 14 and operated by a rod 20 by the foot of the operator for causing the machine to run continuously or intermittently while the said wheel is being continuously rotated, whereby the latter is locked to the shaft 13 or free to 50 turn on the same at the will of the operator.

To the lower end of the reciprocating rod 5 is removably secured a flat plunger 21, the lower end of which is brought in contact with the upper surface or top of the staple 22 to be set and is guided between two plates, which are secured to the head 2 of the machine and are formed in the manner now to be described.

The plate 23 is provided with a vertical groove 24 of a size to snugly but freely admit the plunger 21, said plate also having an opening formed therein through which the delivery or lower end of the inclined track 25 and guard-bar 26, running parallel with the same, passes for delivering the staples below the plunger. Located adjacent to the plate 23 is a second thin plate 27, having a slot

running a portion of its length, the width of which is a little less than the groove 24, the two plates when united and secured to the head 2 of the machine by screws 28 forming a perfect guide for the plunger and for properly guiding and holding the staple until the same is set through the material to be secured together.

In order to hold the staple to be set in its proper position to be struck or operated by the plunger 21, a spring-plate 29 is employed, the upper end of which is secured by the upper two screws 28, which hold the several parts previously described together, said plate being susceptible of a slight adjustment by the elongated openings 30 formed therein through which the said screws are passed, and forming a part of the spring-plate is a lug 31, passing loosely through the slot in plate 27, having an inclined edge 32, which is received by a correspondingly-shaped groove 33 formed in the end of the track, the oppositely-located shoulders 34 formed on said lug abutting against the end of the track on either side of the groove formed therein, whereby a sufficient width is given the lug for holding the staple in a positive position and further holding the same until it is struck by the downward movement of the plunger. The lower or delivery end of the track is slightly curved, as shown, in order to cause the staples to assume a true vertical position before they move under the plunger 21. The forward or free end of the lower jaw is provided with the usual die 35 for turning the legs of the staple inwardly after the same are forced through the material to be united. The staples are fed to the track automatically in the manner now to be described, whereby the latter is constantly filled along its entire length in order to insure the true and perfect working of the machine at all times and under all conditions.

Secured to the rear end of the body 1 of the machine is a bracket 36, the upper end of which rigidly supports a spindle 37, over which the tubular extension 38 of the cylindrical receptacle 39 is loosely passed and is adapted to turn thereon, and to the said tubular extension is secured a belt-wheel 40, over which a belt 41 of any suitable design is passed for imparting a rotary motion to the receptacle.

To the projecting end of the power-shaft 13 is secured a belt-pulley 42, and loosely journaled upon a spindle secured to the body of the machine is an idle belt-pulley 43, over which wheel and pulleys the said endless belt 41 passes, as best shown in Fig. 6 and for the purpose previously described.

The receptacle 39 is provided with a series of plates or wings 44, arranged around its inner circumference, which elevate the staples located in the bottom of the receptacle when the latter is rotated to a height to allow the staples to drop by gravity into the stationary hopper 45, fixed to the projecting spindle 37.

The inclined track 25 leads from the open end of the said hopper and is in a position to properly receive a suitable number of staples as they pass through the hopper to always 5 keep the track full from its receiving to its delivery end, the remaining staples or those that are not received or caught by the track dropping to the bottom of the receptacle, where they are in a position to be again elevated.

At a suitable distance from the upper or receiving end of the track 25 a bend of compound curvature is formed, as shown at 46, which operates to prevent the staples from 15 remaining at that end of the track.

The removable end of the receptacle is provided with an opening 47, through which the upper end of the track 25 projects, and surrounding said opening and located on the inner side of said end of the receptacle is an annular depression 48, which operates to direct staples that have not been properly placed or properly dropped on the track back to the bottom of the receptacle.

Secured to the removable end of the receptacle, concentric with the annular depression 48, is a ring 49, the size of which is less than the circumference of said depression, whereby a space is left to permit the free passage of 20 the fasteners that happen to drop into the said depression, said ring being secured to the end of the receptacle by lugs 50, projecting from the ring, and screws passing through the lugs and into the end of the receptacle. 30 Should the staples become linked or coupled, which often happens, and one of them is on the track properly, the bristles secured to the inner circumference of the ring 49, which forms a circular brush, strike the staple or 35 staples displaced or carried by the one on the track and brushes it off, leaving the one in proper position on the track, the other falling back within the receptacle to be elevated again with the remaining ones.

In practice the belt-wheel 40 may form an integral part of the receptacle 39, thereby reducing the parts, and consequently the cost of manufacture, and further render the parts 45 more durable.

By referring to the drawings it will be seen that the forward ends of the track 25 and guard 26, located above the same, are made adjustable by screws 51 and 52, passing through oppositely-located lugs 53 and 54, forming a 50 part of the stationary jaw 2, the ends of which are brought in contact with the rail and guard, respectively, the same being pivotally secured near their upper ends by screws 55, passing through them and into an extension 56, forming 55 a part of the body of the machine.

By the construction as above described it will be seen that the forward ends of the track 25 and guard 26 may be accurately adjusted in respect to the opening formed in the head 60 through which the staples pass, which is very important. Otherwise through any inaccuracy in the formation of the machine the sta-

bles would not be properly fed under the plunger located within said head, and, further, it is necessary that the forward end of the guard 70 be properly adjusted in respect to the track in order that the staples may be properly held in position upon that end of the track before they enter the head of the machine, the guard being so adjusted as to hold the 75 staples one behind the other.

Referring back to the stationary jaw of the machine, the delivery end of the track, and the spring-actuated lug coöperating therewith, it will be seen that when the plunger 80 comes in contact with the staple supported on said lug the latter is forced outwardly as the staple is forced downward; but the lug remains in frictional yielding contact with the staple until it enters the guideway below 85 the track. Thus it will be seen that the staple is held in a proper position during the entire operation and cannot turn or become displaced, as is usually the result in other staple-setting machines.

When the track 25 is filled with staples and the machine set in motion by the power-shaft 13, the enlarged part of the cam 15 is brought in contact with the rear end of the lever 16, forcing the forward end of the same toward 90 the stationary jaw 2, and thus holding the material to be operated on between said jaws. After the lever has been moved to its highest position the enlarged portion of the cam 12 comes in contact with the upper arm of the 100 fork forming the rear end of the lever 9, forcing the plunger in a downward direction, its lower end coöperating with a staple in the manner previously described. During the above operation the rotating receptacle is 105 continuously operated in order to keep the track 25 filled with staples in order to insure the perfect working of the machine, whereby a staple will be positively set at every complete rotation of the power-shaft.

A very important feature of my invention is the feeding of the material to be operated on in direct contact with the lower surface of the stationary jaw, which operates as a 115 guide for the operator, the material being held in a position while the staple is being set by the lower movable jaw.

It is obvious that the machine is susceptible of various mechanical changes without departing from the nature of my invention. 120 For instance, the rotating receptacle may be operated by any other well-known means.

By referring to Figs. 7 and 8 of the drawings it will be seen that a circular band 57 is secured to one end of the receptacle 39 of a 125 size in circumference to freely pass around the upper or receiving end of the hopper 45 and revolves about the latter, whereby only those staples that drop and pass through the hopper can possibly come in contact with the track and other parts coöperating therewith. It is further to be observed that by the employment of the bend 46 in the track 25 and the coöperation of the circular brush with said

portion of the track the staples are started down the track, leaving the upper end of the same free to receive additional staples.

Having fully described my invention, what I claim is—

- 5 1. A staple-setting machine, comprising a stationary head, a plunger reciprocated within the same, a rotating receptacle, an opening formed in one end of the same, an adjustable 10 inclined track leading from the stationary head and passing through said opening, and projecting into said receptacle, a guard-bar adjustable in respect to said track, means forming a part of said receptacle, for elevating the staples contained therein, and a stationary hopper located over the upper end of said track for receiving the staples as they drop, and delivering them to the track, as and for the purpose described.
- 15 2. A staple-setting machine, comprising a stationary head, a plunger reciprocated within the same, a receptacle for containing staples, an adjustable inclined track leading from the stationary head, having its upper end 20 located within the said receptacle, a guard-bar adjustable in respect to said track, means for elevating the staples contained within the receptacle, and a stationary hopper located over the upper end of said track for receiving the staples, as they drop, and delivering them to the track, as and for the purpose described.
- 25 3. A staple-setting machine comprising a stationary head, a lower jaw, a reciprocating plunger located within said head, means for operating said plunger, a rotating receptacle for containing staples, means located within said receptacle for elevating said staples, a stationary hopper located in said receptacle, 30 a track coöoperating with said hopper for receiving the staples from the hopper, a circular brush secured to said receptacle, and encircling the track, and means for rotating said receptacle, substantially as described.
- 35 4. A staple-setting machine comprising a stationary head, a lower jaw, a reciprocating plunger located within said head, means for reciprocating said plunger, a rotating receptacle, an opening formed in one end of the 40 same, an inclined track leading from the stationary head and passing through said opening and into said receptacle, a circular brush secured to the latter and encircling said track, wings secured to the inside of said receptacle for elevating the staples contained therein, a stationary hopper for receiving the
- 45 staples as they drop and delivering them to the track, and means for rotating said receptacle, substantially as described.
- 50 5. In a staple-setting machine, a rotating receptacle, wings arranged around the inside of the same, a stationary hopper located within said receptacle, a circular brush secured to the latter, and an inclined track located at the delivery end of said hopper and passing 55 through said brush, substantially as described.
- 55 6. In a staple-setting machine, a rotating receptacle having an opening formed in one end of the same, a brush encircling said opening and secured to said receptacle, an inclined track passing through the opening and brush and projecting inside of the receptacle, substantially as described.
- 60 7. In a staple-setting machine, a rotating receptacle, an opening formed in one end of the same, an annular depression located around said opening, a circular brush secured to said end of the receptacle and encircling the opening, and means for securing the brush whereby a suitable space is left between the brush and receptacle, as and for the purpose described.
- 65 8. In a staple-setting machine, an inclined track adjustably secured to the same, and a guard-bar running parallel with said track and also adjustable in respect to the latter, substantially as described.
- 70 9. In a staple-setting machine, a rotating receptacle for containing staples, a hopper located within the same for receiving the staples, an annular band secured to one end of said receptacle and of a size to freely encircle the upper or receiving end of said hopper, and means for receiving and guiding the staples from the latter, substantially as described.
- 75 10. In a staple-setting machine, a rotating receptacle for containing staples, means forming a part of said receptacle for elevating the staples by the rotation of said receptacle, a stationary hopper for receiving the staples as they drop, and a track and guard-bar leading from said hopper, and adjustably secured to the said machine, and in respect to one another, substantially as described.

In testimony whereof I affix my signature in presence of two witnesses.

CHARLES SEBASTIAN.
